(57) **CLAIM**

The ornamental design of a power tool handle portion, as shown and described.

DESCRIPTION

FIG. 1 is a top perspective view of a power tool handle portion;

FIG. 2 is a bottom perspective view thereof;

FIG. 3 is a front elevational view thereof;

FIG. 4 is a back elevational view thereof;

FIG. 5 is a left side plan view thereof;

FIG. 6 is a right side plan view thereof;

FIG. 7 is a top plan view thereof; and,

FIG. 8 is a bottom plan view thereof.

The features shown in broken lines in the drawings depict environmental subject matter and form no part of the claimed design.
